CLEANING OR POLISHING DEVICE

Albert M. Sieb, East Orange, and Ralf L. Hartwell,
Orange, N. J., assignors to Metal Textile Cor-
poration, East Orange, N. J., a corporation of
Delaware

Application July 1, 1939, Serial No. 282,394

2 Claims. (Cl. 15—105)

This invention relates generally to pads, cloths and like devices for service in the performance of cleaning, polishing and similar operations.

This invention has for an object to provide, in 5 a flexible cleaning and polishing device, a novel composite facing comprising a plurality of spaced high pile or tufted areas of soft textile yarn and a close lying abrasive strip covered area intermediate said yarn areas, whereby the effective surface of the latter areas lie in a plane outwardly offset relative to the plane of the effective surface of the abrasive strip, so that said abrasive strip material is normally held out of contact with a surface to which the yarn areas are applied in use, but which abrasive strip material, by flexing the device, may be brought into contact with the surface being cleansed or polished, at will, for removing adhering dirt or like spots from the surface being cleansed or polished.

10 The invention has for another object to provide a cleaning device comprising a flexible hollow pad-like body or envelope containing a filler of cleansing, polishing, or like material adapted to exude therefrom, said body having on one side 15 a composite facing of the character above mentioned.

Other objects of this invention, not at this time more particularly enumerated, will be understood from the following detailed description of the 20 same.

An illustrative embodiment of this invention is shown in the accompanying drawing, in which:

Fig. 1 is an edge view of one form of cleaning and polishing device according to the invention; 25 Fig. 2 is a plan view showing the novel composite facing of the device; Fig. 3 is a fragmentary edge view of the device as disposed for bringing into use the abrasive strip material of the composite facing thereof; and Fig. 4 is a fragmentary sec- 30 tional view, taken on line 4—4 in Fig. 2, but drawn on an enlarged scale.

Similar characters of reference are employed in the above described views, to indicate corresponding parts.

35 The illustrative embodiment of the device, as shown in the drawing, comprises a hollow comparatively thin, flat and flexible bag-like body or envelope 10, comprising, on one side, a porous 40 facing of plain textile fabric 11 and, on the other side, a composite facing of the kind hereinafter described; the registered margins of these facings being secured together by suitable binding stitching 12. The interior of the bag-like body or envelope 10 is filled with a suitable cleaning agent

(not shown) adapted to be exuded, in the use of the device, through the facing 11, the textile fabric which composes the latter being sufficiently porous to admit of such effect.

The novel composite facing, which constitutes 5 the means for optionally abrading or scraping and polishing the surface under treatment by the device, comprises a base fabric 13, preferably a textile fabric. Certain spaced areas of said base fabric 13 are provided with rows of filamentary 10 pile forming tufts or bunches 14, preferably made by sewing a tufting yarn 15 through the base fabric 13 to form the yarn into loops of suitable length which project from the exterior surface of the base fabric; said loops being cut through 15 the bights thereof to produce the desired filamentary piling, the surface extremities of which are offset a substantial distance outwardly of the base fabric 13 to thereby provide an effective 20 polishing material surface. Disposed intermediate the areas formed by the rows of tufted piling 14, is a strip of abrasive material 16 of suitable width disposed in flat lying extension 25 across the exterior surface of said base fabric 13. Said abrasive strip 16 being flatly contiguous to the base fabric 13 is in consequence, disposed in a plane beneath or within the plane of the effective 30 polishing material surface provided by the areas covered by the filamentary pile forming tufts or bunches 14. The abrasive strip 16 may, broadly speaking, be made of any material suitable to effect, when rubbed over and in contact with a surface engaged thereby, a scraping or 35 abrading action. Preferably, however, said abrasive strip comprises a body of knitted metallic wire or ribbon, the interengaged loops of which provide a multiplicity of abrading or scraping elements. The abrasive strip 16 is secured in the described assembled relation to the device by 40 the stitching 12 which engages the respective ends thereof, or may be otherwise secured in any convenient manner.

In the use of the device, the porous facing 11 of the bag or envelope 10 is applied to and rubbed 45 over the surface desired to be cleaned, e. g. the surface of a window pane. During such operation, a portion of the cleansing agent contained in the bag or envelope 10 will be exuded through the facing 11 and applied to the surface operated 50 upon with cleansing effect. This initial cleansing operation having been accomplished, the device is reversed and composite facing is thereupon flatly applied to and rubbed over the surface under treatment for removing traces of cleansing 55

agent and polishing said surface. In this phase of the operation the pile forming tufts or bunches 14 will engage the surface treated with polishing effect, and since the effective polishing area of 5 the composite facing formed by the projected extremities of the pile forming tufts or bunches 14 is located in an outwardly offset plane relative to the plane of the abrasive strip 16, the latter will be fended away and not brought in 10 contact with the surface being polished. It frequently occurs, however, that the surface under treatment is possessed of adhering spots or encrustations of dirt, paint or other foreign substance necessary to be removed to attain 15 thorough cleansing. In such case the abrasive strip 16 is utilized and rubbed over such spots or encrustations with scraping or abrading effect which, by the involved attrition, removes the spots or encrustations. To bring said abrasive strip 16 into service, the outlying pile areas are folded, flexed or turned upwardly to 20 incline away from the surface under treatment (substantially as shown in Fig. 4), thus removing these parts so that the abrasive strip 16 may be brought to bear upon the surface being cleansed.

From the above it will appear that the novel device according to this invention provides a very 30 practical and efficient cleansing and polishing means.

While the novel composite facing provided by the spaced areas of pile forming tufts or bunches 14 and intermediate area of abrasive material 35 is above described as a component part of a cleansing agent containing device, it will be understood that this invention is not necessarily to be limited to such combination, since the composite facing may be used alone for polishing, dusting and spot removing operations, i. e. the 40 cleansing agent containing bag or envelope 10 may be omitted and the composite facing material may be made up as a simple wiping cloth, unit or in any other suitable form.

It will be noticed, by inspection of the drawing, that the filamentary pile forming tufts or bunches 14, incorporated in the composite facing material, are preferably arranged in laterally spaced parallel rows. This is a novel and 45 advantageous disposition thereof, since, in use, intermediate clearance spaces 17 are provided through which dust, dirt, etc. dislodged from a

surface, under treatment, may accumulate and pass away.

It will be understood that various modifications as to size and shape of the device, and as to materials, size, shape, arrangement and grouping of the polishing and abrasive elements making up the composite facing material are possible within the spirit and scope of this invention. It is therefore intended that all matter contained in the above description or shown in the 10 accompanying drawing shall be interpreted as 5 illustrative and not in a limiting sense.

We claim:

1. In a cleansing device, a facing of flexible base material, adjacent areas of said base material being respectively provided with outwardly projected filamentary material tufted therethrough and a section of abrasive metallic fabric secured to said base material in closely contiguous overlying relation thereto so as to be backed 15 thereby, the effective surface of the projected filamentary material lying in an outwardly offset plane relative to the plane of said abrasive fabric, whereby, when the base material is flatly applied to a surface to be cleaned, said abrasive 20 fabric is spaced out of operative contact with said surface, but may be brought into operative contact therewith by flexing the filamentary material bearing areas of said base material 25 away from said surface.

2. In a cleaning device, a composite facing material comprising a flexible base material, adjacent areas of said base material being respectively provided with cut piling of soft textile yarn 30 tufted therethrough to project outwardly therefrom and a section of abrasive material formed by knitted metallic fabric secured to said base material in closely contiguous overlying relation thereto so as to be backed thereby, the effective surface of said textile yarn piling lying in an 35 outwardly offset plane relative to the plane of said abrasive fabric, whereby, when the base material is flatly applied to a surface to be cleaned, said abrasive fabric is spaced out of operative contact with said surface, but may be brought into 40 operative contact therewith by flexing the piling bearing areas of said base material away from 45 said surface.

ALBERT M. SIEB.

RALF L. HARTWELL.
